UNITED STATES PATENT OFFICE.

HAZOR J. SMITH, OF CHICAGO, ILLINOIS, ASSIGNOR, BY DIRECT AND MESNE ASSIGNMENTS, OF ONE-FOURTH TO WILLARD REID AND ONE-HALF TO ALFRED HASTINGS CHAPIN, BOTH OF SPRINGFIELD, MASSACHUSETTS.

ICE-BLOCK FREEZER.

Application filed June 5, 1920, Serial No. 386,885. Renewed October 10, 1922. Serial No. 593,653.

To all whom it may concern:

Be it known that I, HAZOR J. SMITH, a citizen of the United States, residing at Chicago, in the county of Cook and State 5 of Illinois, have invented certain new and useful Improvements in Ice-Block Freezers, of which the following is a specification.

This invention relates to the making of 10 ice for use in connection with refrigeration plants preferably of the private dwelling type and the object of the invention is to devise an apparatus whereby ice may be frozen into small pieces or blocks of predetermined size and shape such as is desirable 15 to use in glasses to cool drinking water.

The invention consists essentially of an outer container or tub and an inner container or can which is spaced from the tub and through which space the cooling or 20 freezing medium is adapted to be circulated. In the can which is adapted to receive the water to be frozen, there is placed an element dividing the can into compartments which compartments are the shape into 25 which it is desired to freeze the water. These compartments have relatively small connecting passages so that after freezing, the element encircled by its ice is removed from the can and the small bits of ice connecting the main lumps in the spaces are 30 readily broken, whereupon the lumps or pieces of desired shape result. The element which is placed in the can preferably has a central vertical stem from which extend 35 a plurality of vertical and horizontal veins or blades.

I have illustrated that preferred embodiment of my invention which is the best of which I am at present informed, in the accompanying drawings in which—

Figure 1 shows a vertical sectional view through the freezer,

Fig. 2 a side elevation of the element which forms the ice cubes, and

Fig. 3 a plan view of that element.

In the drawings, the numeral 11 indicates the tub or outer container of the freezer and 12 indicates heat insulating material carried between its walls. 13 indicates a hollow cylinder connected at its bottom by means of a pipe 14 to the cooling-liquid or gas in a refrigerating plant and 15 indicates the outlet for the cooling medium from which it would flow to the expander

or other element in the refrigerating plant. 55 Within the cylinder 13 is placed the ice can 16 but encircling the can 16 within the cylinder 13 is brine 17. The ice can is provided with a top or cap 18 and within the can is located the ice cube or block-forming element 19.

The block-forming element 19 is composed of a central stem-like portion 20 and this stem merges into a plurality of vertically extending blades or divisions 21, 22, 23 and 24, which blades are preferably tapered to decrease in thickness as their free ends are approached. The blades are of such a width that they just clear the inner periphery of the ice can 16 and they are of such a length 70 that they fit nicely within the length of the can 16 and still provide room for a knob or handle 25 carried by the top of the block-forming element. On the element 19, there are provided a plurality of horizontally extending blades such as 26 and 27, substantially triangular in plan view and which are tapered in thickness similar to the vertical blades or divisions 21 et seq. These blades such as 26 and 27 intersect the vertical divisions such as 24 and they are preferably carried by opposite blades 22 and 24 whereas the other divisions 21 and 23 are free from such triangular blades. In other words, the triangular horizontal blades are 85 preferably carried by alternate vertical divisions or blades.

In operation, the block-forming apparatus 19 is placed in the ice can 16 which in turn is located in the brine in the tub 11. 90 The water to be frozen is put in the can and the cover 18 applied to the can. The refrigerating circuit 14 and 13 and 15 is then put into operation, whereby the cooling medium therein freezes the water in the ice can 16 solid. After it has solidified, the can is opened and the block-forming apparatus 19 is removed by means of its handle 25 and upon removal it is found that all the ice in the can has been frozen around 100 the apparatus 19 and the apparatus and the ice are removed as a unit. Blocks of ice are found formed of a shape bounded on two intersecting sides by the vertical divisions such as 23 and 24 on opposite 105 sides by blades such as 24 and on the fifth side by the curvature of the ice can. These blocks are held together by the small ice

connection which forms between two adjacent blocks where the horizontal blades leave off but these connections can be readily broken whereupon the blocks of ice of the desired shape readily result.

By my method I surround a brine well on all sides with the refrigerating agent which circulates in a thin shelled well or container.

- 10 The water to be frozen is lowered into the brine well in a thin walled container so that the water itself is in turn surrounded on all sides by the brine which serves as a conductor of heat from the water to the
- 15 circulating refrigerating agent. We thus secure quick acting contact on a large surface of the medium to be frozen—with no air spaces between. I obtain an unbroken contact of refrigerating agent en-
- 20 circling a brine well; an insulating well; a

refrigerating agent well; a brine well; and a water well.

What I claim is:

1. In combination, a can adapted to receive water to be frozen, a detachable ice block forming element within the can, comprising a stem, blades carried by the stem extending outwardly to a point in proximity to the sides of the can, alternate blades having webs at right angles thereto. 30

2. The device of claim 1, said webs being carried on that part of the blades remote from the stem, and terminating short of said stem.

In testimony whereof I affix my signature.

HAZOR J. SMITH.

Witnesses:

WILLARD REID,
L. L. COWAN.
